W. P. Goolman.

UNITED STATES PATENT OFFICE.

WILLIAM P. GOOLMAN, OF DUBLIN, INDIANA, ASSIGNOR TO HIMSELF AND SAMUEL B. MORRIS.

IMPROVEMENT IN MOLE-PLOWS.

Specification forming part of Letters Patent No. 26,426, dated December 13, 1859.

To all whom it may concern:

Be it known that I, WILLIAM P. GOOLMAN, of Dublin, Wayne county, Indiana, have invented a certain new and useful Improvement in Mole-Plows; and I hereby declare the following to be a full, clear, and exact description of the same, reference being had to the accompanying drawings, making part of this specification.

The present invention consists, first, in an arrangement for adjusting the pitch of the mole in respect to that of the beam; second, in a provision for inclining the colter at will to compensate for the downward tendency of the mole, as will be hereinafter explained.

In the accompanying drawings, Figure 1 is a vertical longitudinal section at *xx*, Fig. 2. Fig. 3 is a plan. Fig. 4 is a front view of the mole.

K represents a sled provided with standards *L L'* and cross-bars *M M'*.

P is the beam, pivoted in front between the standards *L* by means of a cross-bar *p*.

N is a screw-threaded rod firmly attached to the beam near its rear end and working freely through the cross-bar *M'*.

H represents a hand-wheel or any other suitable form of nut working on the rod *N*, and bearing upon the cross-bar *M'* so as to limit the descent of the beam to any extent desired, or to elevate or permit it to descend at the will of the operator.

Are draft-rods connected at their front ends to the draft-clevis *C*, and at their rear ends to a metallic strengthening-plate attached to the under side of the beam. The clevis *C* is attached to the cross-bar *M*, as represented.

Q is the colter, mortised loosely in the beam near its rear end. At the upper side of the beam the mortise containing the colter considerably exceeds the breadth of the latter, in order to admit of inclining it to any extent desired by means of a cam, *D*.

g are notches in which the cam *D* engages, so as to support the colter at any suitable height in the beam.

R is the mole, pivoted in front to the lower end of the colter *Q*.

E is a lever firmly attached to the mole in the rear of the colter, and extending above the

beam, where it is held in any position desired by a rack, *F*, pivoted to the top of the colter. The lever *E* is of such form that its upper part is precisely at right angles to the sole of the mole, so as to form a constant index of the inclination of the latter. The general contour of the mole is conical, but it is formed with wings *r*, of peculiar form, adapted to gather earth from the sides and compress it against the top of the drain, and also to in a measure counteract the downward tendency of the mole.

A longitudinal groove is formed in the center of the sole, extending from near the point backward, so as to leave a portion of uncom-pressed earth in the center of the drain, in which the water-chamber will be worn, while the sides of the drain are protected from injury.

The operation is as follows: In order to run the mole into the ground, the lever *E* is drawn forward and there retained until the mole has attained the requisite depth. The lever is then so placed as to set the mole at any pitch desired, but always with a downward tendency, in order that the earth may be forcibly compressed against the top of the drain, and in order to relieve the rod *N* and other parts in a measure from the strain to which they would be thereby subjected, the colter is inclined backward, so as to give it an upward tendency, to counteract the downward tendency of the mole. It will be evident that as the imple-ment is drawn through the ground the respective edges of the colter will forcibly press against the rear end of its mortise on the under side of the beam, and against the forward end on the upper side of the same. All that is need-ful therefore in order to regulate the inclina-tion of the colter is to adjust the cam *D* so as to support the front of the upper end of the colter at the proper point, thereby limiting the degree of backward inclination which it will assume below the beam.

I do not claim broadly attaching a lever rig-idly to a mole or plowshare in order to adjust its pitch.

I claim as new and of my invention herein and desire to secure by Letters Patent—

1. The lever *E*, rigidly attached to a pivoted

mole, R, in the described combination with the rack F, the whole being constructed and arranged and operating substantially as and for the purposes set forth.

2. The cam D in the described combination with the colter Q and adjustable pivoted mole R, operating substantially as and for the purpose set forth.

In testimony of which invention I hereunto set my hand.

W. P. GOOLMAN.
